IRONING MACHINE (PAD DRIER)

Peter Eduard Geldhof, Syracuse, N. Y., assignor
to Easy Washing Machine Corporation, Syracuse, N. Y., a corporation of Delaware

Application June 4, 1932, Serial No. 615,431

6 Claims. (Cl. 68—9)

This invention relates to certain new and useful improvements in ironing machines.

It is found that in the use of ironing machines, particularly of the small motor-driven household type that the padding of the ironing roll, which usually includes a felt pad and a fabric covering, becomes damp in use, more particularly as a result of moisture acquired from the dampened article to be ironed, with the result that as ironing continues the operation may gradually become less and less efficient, and the main object of this invention is to provide a novel construction of ironing machine including a means for drying the padding specifically by the use of a current of air.

Other objects and advantages relate to the details of the structure and the form and relation of the parts thereof, all as will more fully appear from the following description taken in connection with the accompanying drawing, in which:

Figure 1 is a front elevation partially in section of an ironing machine of this invention.

Figure 2 is a section taken on line 2—2, Figure 1.

Figure 3 is a view similar to Figure 1 of a modified form of machine.

The ironing machine as illustrated comprises a gear housing 1 which may include also a motor housing 2 for driving the gearing within the housing 1. Gear 3 may be positioned externally of the housing and mounted on a shaft journaled in and extending into the housing and driven from the gearing therein to rotate gear 3.

The ironing roll comprises a hollow metallic cylinder 4 having a multiplicity of perforations 5 extending through its wall. Upon this cylinder 4 is secured any usual padding 6 which may include an inner layer of felt material 7 and an external covering of fabric 8. The ironing roll may 40 extend laterally from the gear housing and the end adjacent the housing is provided with a closure disk 9 formed with internal gear-teeth 10 adapted to mesh with the gear 3 for rotating the ironing roll. Intermediate the length of the ironing roll there is provided a bearing disk 11 fitting tightly within the roll.

For the purpose of securely mounting the roll for rotation, casing 1 is formed with a tubular boss 12 within which one end of a tubular support 13 is rigidly secured. This tubular support is of less length than the length of the ironing roll and extends through journals 14 and 15 formed in the closure disk 9 and the bearing disk 11 respectively.

The tubular support 13 is arranged axially with

respect to the ironing roll so that the latter may rotate freely about it.

An ironing shoe 16 is provided for movement toward and from the roll and as shown, has a supporting member 17 pinned to a rocking tube or shaft 18, which tube is journaled in a second tube 19 carried from the gear housing. Tube 19 may have an additional support in the form of a leg or legs 20, as illustrated. The ironing machine may be supported on any suitable table 10 or the like and there is here illustrated a hollow base 32 to which the machine may be secured if desired, or upon which it may rest without securing.

The description up to this point is applicable to all of the figures of the drawing, but in Figure 1 there is additionally illustrated a small electric motor 21 positioned within the roll at the end beyond the bearing disk 11 and as shown, the motor casing is provided with an externally threaded boss 22 threaded into the outer end of the tubular support 13 so that the tubular support 13 becomes also a support for the motor and the cable 23 containing the electrical conductors for supplying current to the motor may be led out through the tube 13 to the gear housing for connection to a switch member for closing a circuit to the motor when desired, or simultaneously with the closing of the circuit to the motor within the housing 2.

A small fan 35 is mounted on the armature shaft of motor 21 and is adapted to draw air from the chamber within the roll between the closure disk 9 and the bearing disk 11 through openings 26 in the bearing disk 11 and eject the air through a perforated disk or cap 24 secured in the outer end of the roll. This fan acts by producing pressure below atmospheric in said chamber to draw air through the perforations 5 and through the padding 6 upon the roll and in this manner acts to evaporate and expel the moisture from the padding and to maintain it at a degree of dryness desired.

As the motor and fan are confined within the roll the inclusion of this feature in an ironing machine as shown in Figure 1 does not require additional space for use or storage, and the assembly is compact, economical and efficient.

The ironing machine illustrated in Figure 3 is adapted to effect the same result as that described in connection with Figure 1, but is perhaps a less preferred embodiment of the invention.

In Figure 3 the supporting tube 13 is formed with a multiplicity of perforations 25 extending through its wall and placing the interior of the

tube in communication with the interior of the roll between the closure disk 9 and the bearing disk 11 and through the openings 28 in the bearing disk 11 with the end portion of the roll beyond said disk.

In this construction the outer end of the roll is closed substantially air-tight by the cap 27. A tube or conduit 28 penetrates the wall of the supporting tube 13 and leads to a fan housing 29 within which there is arranged a suitable fan 30 driven by small electric motor 31. Preferably, as shown, conduit 28 passes downwardly through the upper wall of the hollow base 32, and the fan housing 29 and motor 31 are secured to and positioned within the hollow base. With this construction as the roll is closed air-tight except for the perforations 5 through its wall, the fan 30 acts to suck air from supporting tube 13 from the space within the roll and thereby draws air through the padding and through the perforations 5 to effect drying of the padding in the manner described in connection with Figure 1.

Although I have shown and described specific structures constituting embodiments of my invention, I do not desire to restrict myself to the details of form, construction or arrangement, as various changes and modifications may be made within the scope of the appended claims.

I claim:

1. An ironing machine comprising a gear housing with gearing therein, an external gear driven therefrom, a tubular ironing roll comprising a perforated metallic shell and padding therearound, a tube rigidly mounted in the gear housing and extending therefrom a distance less than the length of the roll and disposed within and axially of the roll, a closure disk for the end of the roll adjacent the gear housing and formed with an internal gear meshing with the said external gear, a bearing disk mounted within the roll intermediate the length of said roll, said disks journaled on said tube, and mechanical means for withdrawing air from the space within the roll between said disks.

2. An ironing machine comprising a gear housing with gearing therein, an external gear driven therefrom, a tubular ironing roll comprising a perforated metallic shell and padding therearound, a tube rigidly mounted in the gear housing and extending therefrom a distance less than the length of the roll and disposed within and axially of the roll, a closure disk for the end of the roll adjacent the gear housing and formed with an internal gear meshing with the said external gear, a bearing disk mounted within the roll intermediate the length of said roll, said

disks journaled on said tube, and mechanical means for withdrawing air from the space within the roll between said disks, including an electric motor positioned within the roll, and a fan driven by said motor.

3. An ironing machine comprising a gear housing with gearing therein, an external gear driven therefrom, a tubular ironing roll comprising a perforated metallic shell and padding therearound, a tube rigidly mounted in the gear housing and extending therefrom a distance less than the length of the roll and disposed within and axially of the roll and having along the length thereof between the disks hereinafter claimed a multiplicity of perforations extending through its wall, a closure disk for the end of the roll adjacent the gear housing and formed with an internal gear meshing with the said external gear, a bearing disk mounted within the roll intermediate the length of said roll, said disks journaled on said tube, and mechanical means for withdrawing air from the tube and hence from the space within the roll between said disks.

4. An ironing machine comprising a gear housing, an elongated tube rigidly mounted in the housing and extending laterally therefrom, a hollow cylindrical ironing roll journaled on said tube for rotation thereon and having a plurality of perforations extending through its wall, padding surrounding said roll, and means for withdrawing air from the interior of the roll including an electric motor mounted on said tube within the roll and a fan driven by said motor.

5. An ironing machine comprising a hollow base, a gear housing mounted thereon, a cylindrical roll, a tube rigidly mounted in said gear housing extending laterally therefrom and adapted to support said cylindrical roll, and said tube having perforations through its wall, closure disks for the opposite ends of said cylindrical roll, a padding surrounding the roll, a conduit in communication with said tube, and a fan mounted within the hollow base and in communication with said conduit.

6. In an ironing machine, a hollow cylindrical ironing roll having a plurality of perforations, a tube mounted in said ironing roll having means extending therefrom and in contact with the interior of the ironing roll for the support thereof, a motor and fan mounted in said ironing roll for withdrawing air from the interior of said ironing roll and carrying with it moisture drawn through said perforations, said motor having leads extending thereto through said tube.

P. EDUARD GELDHOF.
